CLASP

David M. Goodrich, New York, N. Y.

Application July 11, 1936, Serial No. 90,069

6 Claims. (Cl. 24—263)

This invention relates to improvements in clasps, and this application constitutes a continuation-in-part of the division subject matter contained in my co-pending application Serial No. 73,315 for Garment supporter, filed April 8, 1936.

One of the main features of this invention resides in a clasp which may be releasably attached to the fabric of a shirt or other delicate flexible material without mutilating the same.

Another feature of the invention is to provide a clasp which consists of a recessed body member and a key slidably insertible into the recess of the body member to securely grip a flexible material therebetween. Whereas, I am aware that clasps having sliding wedge keys have been devised, my improved clasp distinguishes thereover in a novel manner for the reason that the key may be inserted into either end of the recess to render the same convenient for assembly and disassembly of the key and the recess member by either a right or left handed person, especially when the clasp is to be applied or removed from a shirt or other garment when in position upon a wearer.

A further feature of the invention is to provide a clasp in which the gripping key may be locked against sliding movement with respect to the body member to overcome any possibility of the accidental sliding of the key member or body member relative to each other which may be caused by side pulling strains imparted to the clasp.

A further object of the invention is the provision of a clasp having the above mentioned feature of utility and construction which is simple and inexpensive of manufacture, and which may be made of various materials and designs to be attractive when displayed upon outer garment apparel.

Other objects of the invention will appear as the specification is proceeded with and read in conjunction with the accompanying drawing, in which:

45 Figure 1 is a perspective view of my improved clasp used in association with a trousers supporter, the latter being shown in position upon a wearer.

Figure 2 is an enlarged detail vertical sectional view on the line 2—2 of Figure 1.

Figure 3 is a perspective view of the clasp with the parts thereof in separated condition.

Figure 4 is a perspective view of a modified form of clasp with parts in separated condition.

55 Figure 5 is a horizontal sectional view of the

clasp shown in Figure 4, but with the coating parts in locked position upon a piece of flexible material.

Referring to the drawing by reference characters, and more particularly to the form of my invention shown in Figures 1 to 3 inclusive, the numeral 10 designates my improved clasp in its entirety, and which is shown in Figure 1 of the drawing as being used in connection with a trousers support 11. The clasp member 10 is 10 illustrated as being attached to the exterior of a shirt 12 whereas the supporting means 11 suspended from the clasp 10 is employed for supporting a pair of trousers 13. Although I have specifically illustrated the clasp 10 as being used 15 for the purpose above mentioned, it will be appreciated that the clasp 10 has many other uses, and I do not wish to restrict the invention to any particular use.

The clasp 10 includes a flat body member 14 20 which is shown in the drawing as being of a circular disklike shape and extending across one of the flat faces of the body member is a recess 15, the side walls of the said recess being straight and parallel and undercut as at 16. By extending the recess 15 entirely across the face of the body member 14, opposite ends of the recess open at opposite side edges of the body member for a purpose to be presently explained. While I have shown and described the body member 30 14 as being of circular disk shape, it is obvious that the same may be elongated or other desired configuration without departing from the function of the same as will be hereinafter more fully appreciated.

The body member 14 may be made of any 35 composition of material, and various shapes or designs, and the circular disk-like shape illustrated in the drawing is but one example.

Releasably associated with the body member 40 14 is a key member 17 having straight parallel beveled side edges 18—18. The key member 17 is a width to freely slide into the recess 15 with the beveled edges 18—18 coating with the undercut walls 16—16 of the recess for the purpose 45 of guiding the key member in its sliding movement and for preventing lateral separation of the key member and body member relative to each other. The end edges 19—19 of the key member 17 are curved to conform to the curvature of the peripheral edge of the body member 14, and the said curved edges 19—19 are flush with the peripheral edge of the body member when the key member is fully inserted therein. The key member 17 may be made of any suit- 50 55

able material and preferably of the same material as that from which the body member 14 is constructed, in order that the appearance of the two members may coincide when in assembled 5 relation.

When applying the clasp 10 to one side of a piece of flexible material such as the exterior of the shirt 12, the body member 14 is applied flat against the outside of the material with the recess 15 facing inwardly. The key member 17 is applied to the inside of the material and the operator after seating a portion of the material into the recess 15 proceeds to insert the key member 17 into the recess 15 through either end thereof. When the key member 17 is fully inserted as shown in Figure 2 of the drawing, that portion of the flexible material seated in the recess is securely gripped, thus the clasp member is in fastened position upon the shirt material.

20 From the foregoing description, it will be appreciated that by having the recess 15 open at opposite ends of the body member 14 that the key member 17 may be conveniently inserted by either a right or left handed user.

25 In Figures 4 and 5 of the drawing, there is illustrated a modified form of the invention wherein the same construction as previously described is retained but in which a means is provided for locking the key member 17 and body member 14 against movement relative to each other. The locking means includes a flat element 20 pivoted centrally of the disk body 14 as at 21. The opposite ends of the elements 20 are bent inwardly to provide flanges 22 which overlie the peripheral edge of the body member 14. The flanges 22 may be moved clear of opposite ends of the recess 15 by imparting a turning movement to the element 20 to enable insertion of the key member 17 or during its removal from the recess 15, but when the key member 17 is in an inserted position within the recess 15, the element 20 is turned so that the flanges 22 overlap the ends of the key member 17. With the element 20 in locking position, it will be appreciated that any strain upon the clasp which might tend to cause a sliding movement of the body member 14 and key member 17 relative to each other is prevented.

50 While I have shown and described what I consider to be the most practical embodiments of my invention, I wish it to be understood that such changes and alterations as come within the scope of the appended claims may be resorted to if desired.

Having thus described the invention, what I claim as new and desire to secure by Letters Patent of the United States, is:—

1. A clasp member adapted to be detachably secured to one side of a piece of flexible material comprising a flat body having a recess extending 55 the length of one side thereof, the walls of said recess being parallel and undercut, said recess adapted to have one side of a portion of a piece of flexible material seated therein, and a flat key member having straight parallel side edges slid- 60 able into said recess through either end thereof and from the other side of a piece of flexible material to clamp a portion thereof between said key member and the walls of said recess, and means carried by said flat body for overlying the 65 ends of said recess for releasably locking said

key member against sliding movement in either direction when the same is wholly inserted into said recess.

2. A clamp comprising a body member having a recess extending the length of one side thereof, the opposed walls of said recess being parallel, a key member having parallel side edges slideable into said recess from either end thereof, and means pivotally carried by said body member and movable over the ends of said recess for releasably locking said key member against sliding movement relative to said body member when wholly inserted within said recess.

3. A clasp comprising a disklike body member having a recess provided in one face thereof and extending entirely thereacross, the opposed walls of said recess being parallel and undercut, a key member slideable into said recess from either end thereof and being of a length to extend the length of said recess, said key member having parallel beveled side edges for coacting engagement with the undercut walls of said recess, and a locking member pivoted centrally to the other face of said disklike body member and provided with inwardly extending elements at the ends thereof which overlie the peripheral edge of said disklike body member for movement to a locking position in lapping relation to the ends of said recess to prevent accidental sliding of said key member relative to said body member.

4. A clasp comprising a body member having a channel extending the length of one side thereof, the opposed walls of said channel being undercut, a key member slideable into said channel from either end thereof and being of a length approximating the length of said channel, said key member having parallel beveled side edges for coacting engagement with the undercut walls of said recess, and a pivoted locking member mounted on said body member and provided with inwardly extending elements at the ends thereof for overlying the ends of said channel when the same is turned to a position substantially parallel to the length of said channel to prevent accidental sliding of said key member relative to said body member.

5. A clasp comprising in combination, a pair of separable slidably interfitting members of substantially equal lengths adapted to grip a flexible material therebetween, said members being 50 separable by sliding the same in either of two directions, and a locking member pivoted to one of said members and provided with inwardly extending elements at the ends thereof for overlying the ends of the other of said members to 55 prevent accidental sliding of one member relative to the other.

6. A clasp comprising in combination, a channeled member, a key member slidably interfitting within said channeled member and being of substantially the same length and slideable into and out of either end thereof, and a locking member pivoted to one of the members and provided with inwardly extending elements at the ends thereof for overlying the ends of the channel of said channeled member to prevent accidental sliding movement of one member relative to the other member.
